UNITED STATES PATENT OFFICE.

DAVID DALIN AND JAMES B. C. LOCKWOOD, OF SEATTLE, WASHINGTON.

DAM-GATE-OPERATING APPARATUS.

Application filed March 20, 1926. Serial No. 96,189.

This invention relates to mechanism for operating and controlling large and heavy doors or gates of the type, more especially, employed as a barrier for the passage or 5 tunnel of a dam to regulate the escape of the stream flow, or to confine water above the dam during the construction of the same.

This type of door, as heretofore constructed and operated has been difficult to 10 remove from the tunnel opening by reason of its large size, weight and, more particularly, by reason of the necessity of overcoming the water pressure which acts to hold 15 the door against its seat.

One of the objects of our invention is to provide a door constituted of a plurality of superposed complementary units which may be regulated successively.

20 Another object is to provide conveniently operated means for conveying the door units, individually or in small groups, to and from operable relation with respect to the tunnel opening.

25 A further object is to provide devices for receiving and supporting the units of a door when unemployed.

Other objects and advantages of the invention will appear in the following specification.

30 The invention consists in the novel construction, adaptation, and combination of parts hereinafter described and claimed.

In the accompanying drawings,—

35 Figure 1 is an upstream elevational view of a portion of a dam with devices embodying the invention applied thereto, said devices being shown partly in elevation and partly in vertical transverse section. Fig. 40 2 is a vertical section taken substantially on line 2—2 of Fig. 1. Fig. 3 is a view partly in side elevation and partly in transverse section of door-units hoisting and supporting devices, portions being broken away.

45 Fig. 4 is a detail front elevational view of a portion of one of the door units, the support therefor and the gate guide timbers. Fig. 50 5 is a horizontal sectional view on line 5—5 of Fig. 3. Fig. 6 is a detail elevational view 55 partly broken away and partly in section to illustrate the preferred manner of connecting a hoisting cable to the gate elevator.

In said drawings, the reference numeral 10 represents a portion of a dam structure having therein a waste-tunnel 11 which extends transversely through the dam from the

wall surface 12 thereof. In carrying out our invention we erect a temporary rigid framework comprising at each side of the tunnel at its inlet end a vertically disposed 60 timber 13, hereinafter designated as a jamb, which is juxtaposed with the wall surface 12 of the dam structure, and a second vertically disposed timber 14, or guard as hereinafter termed, in front of each of the 65 jambs.

As shown, the complementary timbers 13 and 14 at each side of the tunnel entrance are held in spaced apart relation by means 70 of planking 15 secured to the outer side surfaces of the respective pairs of timbers and constitute therewith ways within which the door is movable vertically. For relatively large tunnels, said ways are desirably reinforced by means of vertical timbers, such as 75 16, secured to the outer surfaces of the planking assembly of the respective way. Transversely arranged head and sill rails 17 and 18 are provided between the jambs above and below the tunnel opening, the front surface 80 of said rails being in a plane with the front surface of the jambs.

The vertical jamb and guard members 13 and 14 are of lengths to extend to an elevation of at least twice the height of the tunnel. 85 Above the tunnel, said framework is formed in a suitable manner, which, as illustrated, consists of vertical members 19, horizontal members 20, braces 21, and a platform 22 upon which the operators stand when regulating the tunnel barrier or door above referred to.

Said door is composed of a plurality of complementary sections or units 23 disposed horizontally one above another within the 90 opening between the ways and of a length to extend into the latter.

Each of said door units is formed of a uniform rectangular shape throughout its length, the central portion, preferably of 100 wood, and ends of metal. Each of such ends, or boxes 25 is hollow to provide a chamber 26 (Fig. 3), with vertically aligned apertures 27 and 28 in the upper and lower walls of a box. Said apertures are of an elongated shape, preferably elliptical, the major axes of all such apertures being disposed in the same direction, being shown in the drawings as disposed longitudinally of the respective door units. In its front wall, 110 each box is desirably provided with an aperture 29 of rectangular shape, preferably.

For raising and lowering the door units from and into their operative positions, in front of the tunnel, we provide an elevator comprising two vertical tubular members 30 disposed axially of the apertures 27 and 28 of said units at the opposite sides of the door. The elevator members 30 have telescopic connection with rods 31 whose lower ends are secured, as by means of flanged 5 sockets 32 (Fig. 3), to the sill member 18, said rods extending into the members 30 serve to guide the latter in their up and down travel and also serve as axles about which the respective members are rotatable.

15 Near their upper ends said members are turnable and endwise movable in journal bearings 33 secured to the framework. Said elevator members are also rotatable in journal bearing elements 34 (shown in detail 20 in Fig. 6) of a yoke 35, which with the members 30 constitute the referred to elevator. The members 30 are each secured to the yoke against independent longitudinal movement as by means of a collar 36 (Fig. 6) rigidly 25 secured, as by rivets 37, to the respective member, said collar being journaled in a yoke element 34 between its shoulders 38.

To permit the members 30 being thus connected to the yoke, the bearing elements 34 of the latter are each formed of separable parts which are secured together by coupling bolts 39. At the extremity, preferably of each yoke, the same is provided with apertured ears 40, shown in Figs. 3 and 6, 35 to which are engaged the ends of hoisting cables 41, one for each side of the elevator. For clearness only portions of cable 41 are represented in Figs. 1 and 2, said cables being wound about drums 42 (Fig. 1) 40 mounted upon a shaft 43 which is rotatable in journal boxes 44 secured to the upper portion of the framework. For winding said cables upon the drums, said shaft may be rotated by any suitable means, that shown 45 in the illustrated embodiment, consisting of a manually actuated machine 45 located upon the platform 22. Power is transmitted from the machine 45 through the medium of a sprocket chain, indicated by 46, to drive an intermediate shaft 47 from which, in turn, the drum shaft is driven by a sprocket chain, which is indicated by 48.

For engaging the elevator to a door unit, each of the tubular members 30 is provided 55 at its lower end with a collar 49 having at diametrically opposite sides arms 50, see Figs. 3 and 5, which are adapted to pass through the apertures 27 and 28 of the door units when the members 30 are regulated to 60 have their arms 50 disposed longitudinally of a door unit, as shown in Fig. 5, but when the members are rotated to have the arms directed transversely, as shown in Fig. 3, the same are engageable with the box element of 65 a door unit to enable the latter to be carried

by the elevator. The elevator members 30 are turned to regulate the rotary positions of the unit engaging arms by any suitable means, the means shown consisting of operating arms 51 which are adjustably connected 70 to the respective members as by means of clamp screws 52.

Included in the invention are means for releasably supporting the door units when brought thereto by the above explained 75 elevator.

To such end we provide at the inner side of each of the guard timbers 14 a vertical tubular shaft 53 which is sleeved upon a rod 54 which is journaled in a bearing of a 80 bracket 55 (Fig. 3) secured to the respective guard timber 14.

Adjacent its upper end the shaft 53 is journaled in a bearing 56 and above the latter is provided with an operating arm 57 whereby the shaft 53 is rotated to swing an arm 58, which is provided upon the lower end of the shaft, into and from the aperture 29 provided therefor in the adjacent end of 90 a door unit.

Gage device such as 59, Fig. 3, may be secured to some part of the framework to indicate the maximum elevation of the door to be entirely clear of the tunnel opening.

Operation: The door is brought into its closed condition with respect to the tunnel opening by successively piling the door units 23 one upon the other above the sill 18.

When it is desired to open the door the units 23 thereof are elevated singly or in groups of two or more according to the weight of the individual units and to the amount of water pressure acting against the door units to bear the same against door jambs 13. To raise the door units, the elevator, consisting of the yoke 35 and tubular members 30, is lowered to cause its arm elements 50 to enter the boxes 25 of the lowermost unit of a desired load thereof—that is to say, one or more of such units.

100 The arms 50 are turned into positions suitable for passing through the apertures 27 and 28 of the respective box elements by rotating the respective elevator members 30 through the instrumentality of their operating arms 51. The elevator is then lowered by the operator allowing the shaft 43 to turn to effect the uncoiling of the elevator hoisting cables from the respective drums 42.

115 After the elevator has descended to carry the arms 50 into the box chambers of a selected door unit as, for example, the second from the top of the pile, the elevator members 30 are turned to rotate the arms 50 into engageable relation with the unit.

120 Thus arranged the machine 45 is operated to cause the hoisting cables to be rewound upon the drums, whereupon the elevator with its load of two units (in the present in- 130

stance), ascends to the elevation in which are represented the units indicated by 23' in Figs. 1 and 2, or, in other words, to have the lower unit of the load raised into position to receive the supporting arms 58 within the respective apertures 29. These supporting arms are then turned into such apertures and the load deposited thereon by lowering the elevator. When relieved of their load the elevating arms 50 are turned into positions to pass downwardly through the apertures 28 of a door unit and thus lowered with the elevator to pick up a second load and so on, progressively, until the entire door, or so much of it as may be desired, is raised into positions to be supported by the supporting arms 58.

In the raising of the successive loads of door units, the load or loads previously elevated, are raised by being borne upon the elevator while the supporting arms are disengaged from one door unit, after which the entire load then upon the elevator is elevated to have the lowermost unit of the load engaged by the supporting arms 58. It may be mentioned that the door units when located in front of the tunnel opening are held to their seats against the jambs 13 by an unbalanced pressure of water, thereby rendering the removal of the door extremely difficult unless the door is divided into units which can be elevated singly or in groups as permitted in the present invention.

When the door units have been raised above the head rail 17 of the door way frame, so to speak, the units are subjected to water pressure from both sides thereby enabling the elevator to readily raise any accumulation of door units upon the supporting arms 58, because it is only necessary to overcome the weight of the units—less the buoyancy of the same, when submerged or partially submerged in water.

The operation and advantages of the invention will, it is believed, be understood from the foregoing description of the invention. The door and its controlling mechanism is comparatively simple in its construction, it may be installed at small cost, and readily operated.

We do not wish to confine ourselves to the structural details nor to any specific use of the invention except as limited by the terms of the appended claims.

What we claim, is,—

1. In a dam structure having a passage, a door for closing the passage at the upstream end thereof, said door being composed of a plurality of superposed units, an elevator, rotary means carried by the elevator for engaging selectively one of the door units individually or a plurality of units as a group,

and means for operating the elevator to remove said units from the passage.

2. In a structure having a passage, a door for closing the passage, said door being composed of a plurality of superposed complementary units, and manually controlled means adapted to penetrate the uppermost of said units, said means being actuated at a distance from the passage for engaging said units whereby one or more, selectively, of the units are connected to the elevator for conveying the units to and from their closing position with respect to the passage.

3. In a dam structure having a passage extending transversely therethrough, the upstream end of the passage being surrounded by a seat for a door, a door composed of a plurality of units, door supporting means provided above said passage, an elevator, devices carried by the elevator and engageable with the units, said devices being regulated from a position above said passage, and means for operating the elevator to transfer the door units successively from said seat to said supporting means, and for returning the door units to said seat.

4. In a structure having a passage extending therethrough, a door for closing the passage, said door being composed of a plurality of units, ways provided at opposite sides of said passage, a means for raising said door units from said passage and returning the same thereto, means provided upon the elevator for detachably engaging the door units thereto, unit supporting means provided in said ways above the passage, and means to regulate said supporting means to permit said first named means to carry the door units above or below the supporting means therefor.

5. In a structure having a passage and a door-seat surrounding the entrance to said passage, a door composed of a plurality of complementary parts having chambered ends provided with apertures in the upper and lower walls thereof, guide rods extending upwardly through the chambers and apertures at both ends of all of the door parts, an elevator having pipe members mounted for rotary and vertical movements on said guide rods, means turnable with the respective elevator members for engaging said door parts, means for actuating said elevator for effecting the hoisting and lowering of the door parts from and to said door seat, and means provided above the top of said passage for supporting said door parts in their elevated positions.

Signed at Seattle, Washington, this 12th day of January, 1926.

DAVID DALIN.
